(57) **CLAIM**

The ornamental design for a bicycle basket supporting bracket, as shown and described.

DESCRIPTION

FIG. 1 is a front perspective view of a bicycle basket supporting bracket showing our design;

FIG. 2 is a front perspective view thereof similar to FIG. 1 with the basket and clips removed for clarity;

FIG. 3 is a front elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a front perspective view of a bicycle basket supporting bracket showing an alternative design;

FIG. 9 is a front perspective view thereof similar to FIG. 8 with the basket removed for clarity;

FIG. 10 is a front elevational view thereof;

FIG. 11 is a left elevational view thereof;

FIG. 12 is a right elevational view thereof;

FIG. 13 is a top plan view thereof; and,

FIG. 14 is a bottom plan view thereof.

The broken lines show environment and form no part of the claimed design.
